UNITED STATES PATENT OFFICE.

CHARLES E. RICKS, OF DILLON, COLORADO, ASSIGNOR OF TWO-FIFTHS TO CHARLES A. KELLAR, OF DILLON, COLORADO.

GARMENT-CLASP.

1,090,753.

Specification of Letters Patent. Patented Mar. 17, 1914.

Application filed November 26, 1912. Serial No. 733,646.

To all whom it may concern:

Be it known that I, CHARLES E. RICKS, a citizen of the United States, residing at Dillon, in the county of Summit and State 5 of Colorado, have invented new and useful Improvements in Garment-Clasps, of which the following is a specification.

This invention relates to improvements in garment clasps and has particular application to a clasp for use in conjunction with hose supporters and the like.

In carrying out the present invention, it is my purpose to provide a garment clasp whereby the garment will be effectively 15 gripped and which will be constructed in such manner that the portion of the garment to be grasped will be automatically fed into the clasp.

It is also my purpose to provide a device 20 of the class described wherein by means of a pair of jaws and a feeder and a lever controlling the jaws and the feeder, the garment will be fed to the clasp between the jaws and subsequently gripped by the jaws.

Furthermore, I aim to provide a garment 25 clasp which will embrace the desired features of simplicity, efficiency, durability and strength coupled with cheapness of cost in manufacture and marketing and which may be conveniently manipulated.

With the above and other objects in view, the invention consists in the construction, combination and arrangement of parts hereinafter set forth in and falling within the 30 scope of the claims.

In the accompanying drawing: Figure 1 is a plan view of a garment clasp constructed in accordance with the present invention, the same being shown in use. Fig. 2 is a 40 side elevation of the clasp in open position. Fig. 3 is a similar view showing the feeder in initial garment fastening position. Fig. 4 is a transverse sectional view through the clasp. Fig. 5 is a perspective view of the 45 feeder.

Referring now to the accompanying drawing in detail, the numeral 1 indicates what may be termed the stationary jaw of the clasp, while 2 designates the movable jaw 50 which, in the present instance, has one end integrally connected with the adjacent end of the stationary jaw as at 3 and is preferably constructed of springy material, the jaw 2 tending normally to maintain an open 55 position as shown in Fig. 2. Upstanding

from the opposite side edges of the stationary jaw 1 and preferably formed integral therewith are parallel alining pivot posts 4, 4 each provided at its upper end with two apertures 5, 5 disposed one above the other 60 with respect to the jaw 1 and each alining with one of the apertures in the opposite post.

The numeral 6 indicates the manipulating lever preferably formed of a strip of metal 65 bent outwardly as at 7 to form a heel 8, thence at right angles to itself as at 9 to form a locking lug, the bent portion 9 being provided at its opposite side edges with outwardly extending pintles interchangeably associated with the alining apertures 5, 5 in the pivot posts 4, 4. From this construction, it will be seen that when the lever 70 is in the position shown in Fig. 2, that is at approximately right angles to the movable jaw 2, the clasp is open, while when the lever is moved in a forward direction, the heel 8 will engage the adjacent portion of the upper surface of the movable jaw to move the latter toward the fixed jaw. On 75 the other hand, when the lever 6 is moved in a rearward direction the locking lug formed by the bent portion 9 will engage the top surface of the movable jaw and move the latter toward the fixed jaw and into engagement therewith to close the clasp and lock the same in closed position.

Each jaw 1, 2 adjacent to the free end thereof is formed with a series of transversely disposed slots appropriately spaced 80 apart and alternating with the slots in the other jaw, and a series of transversely disposed ribs 11 suitably spaced apart and alternating with the ribs on the other jaw and adapted to be moved into the slots in the 85 opposite jaw, the ribs 11 being formed on the inner confronting faces of the jaw and designed for the purpose of effectively gripping the material of the garment. As shown in Fig. 2, the ribs 11 on the lower 90 jaw are of various heights, the first rib being short while the second is a little higher and the third of a height greater than the second. This formation of the ribs enables the material between the jaws to be grasped at 95 successive increasing pressures.

In order to feed the material of the garment into the clasp or between the jaws thereof when the clasp is in open position, I employ what I term a feeder composed, in 100

the present instance, of a bar 12 having a series of depending teeth 13 and slidably disposed within guides 14, 14 composed of lengths of wire extending longitudinally of 5 the opposite edges of the movable jaw 2 for a portion of its length and each having the opposite ends thereof connected to the respective edge of the jaw, as clearly illustrated in Figs. 1 and 4. Pivotally connected 10 to the lever 6 at the opposite side edges thereof are rods or wires 15 having the free ends thereof pivotally connected to pintles 12^a extending outwardly of the opposite ends of the bar 12 of the feeder, the wires 15 being adapted, in the movement of the lever 15 20 to impart movement to the feeder. It will be noted that each guide 14 adjacent to its forward end is bulged or bent outwardly as at 16 of the adjacent end of the movable 25 jaw, while the rear end of the guide is bulged outwardly of the adjacent portion of the movable jaw as at 17, so that when the feeder is at the free end of the movable jaw, such feeder will be disposed at an angle of approximately 45° to the plane of the movable jaw, while when the feeder is within the bulged portions 17 of the guides such 30 feeder will be in a released position as indicated by the dotted lines in Fig. 2.

30 Extending upwardly from the pintles 12^a are lugs 12^b designed to engage the under surface of the jaw 2 in order that outward swinging movement of the feeder, in the sliding movement thereof, will be avoided 35 so that the adjacent portion of the garment will be brought into the jaws of the clasp.

From the foregoing description taken in connection with the accompanying drawing, the construction, mode of operation and 40 manner of employing my invention will be readily apparent. When the manipulating lever 6 is raised, assuming the same to have been closed, the locking lug formed by the bent portion 9 of such lever disengages the 45 upper surface of the movable jaw 2 and permits the latter to move away from the stationary jaw to open the clasp. Upon the lever reaching a position at approximately right angles to the plane of the movable 50 jaw, the rods or wires 15 impart movement to the feeder bar 12 to move the same out of the bulged portions 17 of the guides and in the continued movement of the manipulating lever the feeder moves along the 55 guides 14 and enters the bulged portions 16 at the forward ends thereof and assumes a position at approximately 45° to the plane of the movable jaw, as shown in Fig. 3. The end of the stationary jaw 1 is now placed 60 adjacent to the fabric of the garment while the heel 8 of the manipulating lever forces the movable jaw toward the fabric and consequently engages the teeth 13 of the feeder with the adjacent part of such fabric so 65 that when the lever 6 is moved in a reverse

direction the fabric is drawn into the clasp and between the jaws thereof, the movable jaw, at this time, moving away from the stationary jaw. After the lever passes the approximate center of its path of movement, the movable jaw is actuated toward the fixed jaw incident to the locking lug formed by the bent portion 9 of such lever engaging with the adjacent surface of the jaw 2 with the effect that the garment is grasped by 75 the ribs 11 of the jaws. Immediately preceding the lever 6 reaching the end of its path of movement to close the jaws, the teeth 13 of the feeder are disengaged from the garment and disposed within the bulged 80 portions 17 of the guides.

It will be seen that the stationary jaw 1 is of less length than the similar dimension of the movable jaw so as to enable the teeth of the feeder to engage the garment at a 85 suitable distance from the edge thereof.

While I have herein shown and described one preferred form of my invention by way of illustration, I desire to have it understood that I do not limit or confine myself to the precise details of construction herein shown and described, as modification and variation may be made within the scope of the claims and without departing from the spirit of the invention. 90

I claim:

1. A garment clasp comprising a pair of jaws, a feeder carried by one of said jaws and adapted for sliding movement along the inner face thereof, and a lever for moving 100 said jaws to closed position and sliding said feeder between said jaws.

2. A garment clasp comprising a stationary jaw, a movable jaw movable toward and away from the stationary jaw, pivot posts upstanding from said stationary jaw, a manipulating lever pivoted between said posts above said movable jaw, said lever being formed to provide a locking lug adapted to move the movable jaw toward the stationary jaw and lock the jaws in closed position in the rearward movement of the lever, and a heel adapted to move the movable jaw toward the stationary jaw in the forward movement of the lever, guides carried by said movable jaw, a feeder slidably disposed within said guides, and connections between said feeder and manipulating lever whereby the feeder will be moved outwardly of the jaws in the forward movement of the lever and moved between the jaws in the rearward movement of the lever. 110

3. A garment clasp comprising a stationary jaw, a movable jaw movable toward and away from the stationary jaw, a lever for manipulating said movable jaw and capable of movement in a forward and rearward direction and formed to provide a locking lug adapted to move the movable jaw into closed position and hold the same in such 120 125 130

position in the rearward movement of the lever, and a heel adapted to move the movable jaw toward the stationary jaw in the forward movement of the lever, a feeder carried by said movable jaw and adapted to grip the garment to draw the same into the clasp, and connections between said feeder and manipulating lever whereby the feeder will be moved outwardly of the jaws

in the forward movement of the lever and moved between the jaws in the rearward movement of the lever.

In testimony whereof I affix my signature in presence of two witnesses.

CHARLES E. RICKS.
